CLAIM

The ornamental design for a base station, as shown and described.

DESCRIPTION

FIG. 1 is a top left front perspective view of a base station in accordance with the claimed design;

FIG. 2 is a front elevation view of the design of FIG. 1;

FIG. 3 is a rear elevation view of the design of FIG. 1;

FIG. 4 is a top plan view of the design of FIG. 1;

FIG. 5 is a left side elevation view of the design of FIG. 1; and,

FIG. 6 is a right side elevation view of the design of FIG. 1. The bottom plan view of the claimed design is omitted as it forms no part of the claimed design and/or is cumulative in view of the remaining figures.

The dash-dash broken lines in the figures (including, e.g., fasteners and openings for receiving such fasteners, etc.) represent unclaimed subject matter and form no part of the claimed design.

The dot-dash broken lines in the figures immediately adjacent the solid lines represent a boundary between claimed and unclaimed subject matter and form no part of the claimed design.
